GAME BOARD

Leon D. Hoffman, Jr., 400 Northwest Drive,
Silver Spring, Md. 20901

Filed May 2, 1966, Ser. No. 2,117

Term of patent 14 years

(Cl. D34—5)

FIG. 1 is a plan view of a game board, showing my new design;

FIG. 2 is a side view of the game board, and

FIG. 3 is an end view thereof.

I claim:

The ornamental design for a game board, as shown.
